UNITED STATES PATENT OFFICE.

JAMES HOEY, OF BROOKLYN, NEW YORK.

EXHAUST-STEAM TRAP.

SPECIFICATION forming part of Letters Patent No. 320,134, dated June 16, 1885.

Application filed April 28, 1885. (No model.)

To all whom it may concern:

Be it known that I, JAMES HOEY, a citizen of the United States, residing at Brooklyn, in the county of Kings and State of New York, have invented a new and useful Improvement 5 in Exhaust-Steam Traps, which improvement or invention is fully set forth and illustrated in the following specification and accompanying drawings.

10 The object of this invention is to provide an exhaust-steam trap which shall be of simple construction, cheap, durable, and efficient in trapping the water of condensation, without itself acting materially as a condenser, and 15 also capable of ready attachment to exhaust-steam pipes, and equally easy of access to its interior should such access at any time be desirable for purposes of cleaning any oily deposit or any dust or dirt collected thereby or 20 adherent thereto.

The invention consists of the apparatus hereinafter described, and particularly set forth in the claim.

In the accompanying drawings, Figure 1 is a 25 transverse diametrical vertical section through the apparatus, and Fig. 2 a plan of the apparatus.

In said figures the several parts are indicated by letters, as follows:

30 A indicates a cylinder, open at top and closed at bottom, except at its two apertures a and b—the former for the entrance of the exhaust-steam, the latter for the exit of the water of condensation entrapped within the apparatus. 35 From the bottom of the cylinder A a tubular extension or inner nozzle rises, being an extension of the aperture a. Above said nozzle, and set partially within the cylinder A, is the inverted cylinder B, secured by the angle strap- 40 braces or A-braces d to the interior of the cylinder A. Said braces are preferably riveted to the cylinder B by rivets h, but secured to the cylinder A by bolts e and nuts g. In the plan, Fig. 2, three of said A-braces are shown, 45 securing the cylinders A and B together; but two, four, or more of such braces may be used, if desired. Three will, however, in most cases be amply sufficient. The bottom edge, f, of the cylinder B should preferably lap or extend 50 below the top edge of the nozzle c a short distance. From one-eighth to one-quarter of an inch will be usually quite sufficient.

Should it be desired at any time for any reason to clean out the bottom of the cylinder A, by simply removing the three bolts e, the 55 cylinder B may be removed and replaced in a very few minutes, the time required for unscrewing and screwing up again said bolts being scarcely appreciable, practically considered. 60

The operation of this apparatus is so simple as scarcely to need description. The device is screwed on top of the exhaust-pipe, which is entered in the aperture a, tapped out to receive it. A waste-water pipe is tapped into 65 the aperture b, and led off to any desirable receptacle, drain, or sewer. When the engine is in operation, the exhaust-steam rises through the nozzle c, throwing or carrying up to and against the inner dome top of the cylinder B 70 any contained water, either condensed in the pipes or entrained with the steam, due to foaming or priming of the boiler. Said water is immediately deflected downward and falls back upon the annular bottom of the cylinder A, 75 while the dry uncondensed steam escapes out of the trap around the cylinder B through the annular space between the cylinders B and A, the water, of course, discharging itself out of the trap through the aperture b. 80

It is not the object to condense any of the steam within this trap, though of course some condensation therein is unavoidable. The apparatus is intended as an efficient trap or dry-plate device to retain any water entrained in 85 the steam and let only the dry steam escape into the air, the water being led away, as hereinbefore described. Thus is prevented the wetting of the roofs of houses through which so many exhaust-steam pipes are protruded 90 in cities, which pipes, if not suitably trapped, keep such roofs constantly wet with water and spray from the steam in summer and caked with ice in winter in cold climates. This evil in most cities amounts frequently to a nuisance. 95 Practical trial has established the thorough efficiency of this trap in perfectly protecting the roof from water and spray and in delivering above the trap only "dry" steam. 100

The cylinders B and A may be made of any suitable material; but they may be very cheaply and durably made of cast-iron, needing neither turning nor boring. A few rivet-holes and bolt-holes only need be drilled. The two holes

a and *b*, being cast in the metal, only require to be tapped out for their screw-threads.

It is obvious that the cylinder *B*, instead of having a dome-top, may be made with either 5 a flat or conical top without departing from the principle of my said invention. The dome, however, is preferable for strength and lightness combined and for its curve deflection. It also presents a neater mechanical appearance 10 than said other shapes.

Having thus fully described my said improvement, as of my invention, I claim—

An exhaust-steam trap consisting of an exterior cylinder, as *A*, open at top and closed 15 at bottom, except by an aperture for the entrance of steam and an aperture for the exit

of water, in combination with an interior closed top cylinder, as *B*, inverted over said steam-aperture, but not closing the same, and secured to said exterior cylinder by radial 20 braces in the annular space between said cylinders, whereby the water entering said trap entrained with said steam is trapped therefrom and discharged below, and the steam permitted to escape otherwise unimpeded through 25 said annular space, substantially as and for the purposes set forth.

JAMES HOEY.
